[57] CLAIM

The ornamental design for multiple outlet surge protector, as shown and described.

DESCRIPTION

FIG. 1 is a perspective view from above of the ornamental design of the multiple outlet surge protector of our invention;

FIG. 2 is a top plan view of the invention of FIG. 1;

FIG. 3 is a side plan view of the invention of FIG. 1;

FIG. 4 is a bottom plan view of the invention of FIG. 1;

and,

FIG. 5 is a front plan view of the invention of FIG. 1.

FIG. 6 is a back plan view of the invention of FIG. 1.
